ATTORNEY

UNITED STATES PATENT OFFICE.

JOHN E. ROUGHAN, OF LIBERTY, INDIANA, ASSIGNOR TO WALTER F. BOSSERT, OF LIBERTY, INDIANA.

SUPPORT FOR CONCRETE REINFORCING MEMBERS.

Application filed April 30, 1927. Serial No. 187,935.

My invention relates to supports or stools designed for supporting the reenforcing members used in the construction of concrete roads and other constructions in spaced relation from the ground or base upon which they are mounted.

It is an object of the invention to provide a device of this character which is inexpensive to produce and which will firmly and rigidly support the reenforcing bars or rods, all as will be hereinafter more fully described and claimed.

Referring to the drawings, which are made a part hereof and on which similar reference characters indicate similar parts:

Figure 1 is a perspective of a support illustrating my invention, and

Figure 2 is a perspective illustrating an application of my invention.

20 In the drawings, reference character 10 indicates a road base or the like upon which reenforced concrete is to be applied for forming a hard surface. In order to strengthen the concrete and prevent it from spreading 25 reenforcing members or bars 11 are combined to form a network embedded in the concrete when it is in place. The network 11 may comprise bars or reenforcing members of angular form and disposed in a substantially horizontal plane, such bars or reenforcing members being connected at their contiguous portions or angles by means of clips 12 or other fastening devices, and forming squares or any other desired designs.

35 As is well-known, the road base or foundation oftentimes may not have a regular or smooth surface, and it is necessary to support portions of the reenforcing network in spaced relation thereto. Also, it is desired to 40 support the reenforcing members at a height such that, when the construction is completed, the reenforcing network will be disposed at a given distance relative to the surface of the same. I therefore provide a 45 support or stool for performing this function.

The support is preferably of cast iron or other inexpensive material and is preferably cast in one piece and, as shown in Figure 1, 50 consists of a relatively large, substantially

flat base 13 and an upright body 14 provided with a bifurcation 15 in its upper end for receiving the reenforcing members and supporting them in the proper relation. The body 14 may be of any desired length in 55 order to suit the requirements and conform to the type of construction for which they are being used.

In lieu of the clips or fastening devices, the support or stool may be placed at the joint with the adjoining portions of the bars disposed in the bifurcated end of the support and in this manner the support will perform the dual function of supporting the reenforcing members and of holding them in 60 65 proper relative position.

It will be obvious to those skilled in the art that various changes may be made in my device, without departing from the spirit of my invention, and I, therefore, do not limit 70 myself to what is shown in the drawings and described in the specification, but only as set forth in the appended claims.

Having thus fully described my invention, what I claim as new and desire to secure 75 by Letters Patent is:

1. A support or stool for reenforcing members of reenforced concrete construction for supporting them in position comprising a relatively large, substantially flat base and 80 an integrally formed upright having its upper end bifurcated to receive said reenforcing members for supporting them above the base upon which they are mounted, substantially as set forth.

2. A support or stool for reenforcing members of reenforced concrete construction for supporting them in position comprising a relatively large substantially flat base and an upright body portion having its upper end 90 provided with a bifurcated portion to receive said reenforcing members for supporting them in spaced relation above the base on which they are mounted, substantially as set forth.

In witness whereof, I have hereunto set my hand at Indianapolis, Indiana, this 26th day of April, A. D. nineteen hundred and twenty-seven.

JOHN E. ROUGHAN.
